US0D1047732S

(12) **United States Design Patent** (10) Patent No.: **US D1,047,732 S**
(45) Date of Patent: ** Oct. 22, 2024

(54) **WATCH**

(71) Applicant: **Chopard International SA**, Prangins (CH)

(72) Inventor: **Karl-Friedrich Scheufele**, Prangins (CH)

(73) Assignee: **Chopard International SA**, Prangins (CH)

(**) Term: **15 Years**

(21) Appl. No.: **29/846,822**

(22) Filed: **Jul. 19, 2022**

(30) **Foreign Application Priority Data**

Mar. 9, 2022 (WO) WIPO114483

(51) **LOC (14) Cl.** **10-02**

(52) **U.S. Cl.**

USPC **D10/32**; D10/38

(58) **Field of Classification Search**

USPC D10/30-39, 128; D14/344; D11/3-5, D11/86-87

CPC .. G04B 19/00; G04B 19/223; G04B 37/1486; G04B 37/005; G04B 37/0041; G04F 7/08; G04F 7/0804; G04F 7/0842; G04F 7/0861; G04F 7/0871; G04F 7/0876; A44C 5/02; A44C 5/00
